(57) **CLAIM**

The ornamental design for massage chairs with a display device and partition, as shown and described.

DESCRIPTION

FIG. 1 is a front right perspective view of a first embodiment of massage chairs with a display device and partition

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front right perspective view of a second embodiment of massage chairs with a display device and partition;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The stipple shading is used to indicate wood panels. The broken lines in the drawings illustrate portions of the article that form no part of the claimed design.
